(57) **CLAIM**

The ornamental design for a door component extrusion assembly, as shown and described.

DESCRIPTION

FIG. 1 is a front isometric view of a door component extrusion assembly showing our new design.

FIG. 2 is a front elevation view of the door component extrusion assembly of FIG. 1.

FIG. 3 is a rear elevation view of the door component extrusion assembly of FIG. 1.

FIG. 4 is a left side elevation view of the door component extrusion assembly of FIG. 1.

FIG. 5 is a right side elevation view of the door component extrusion assembly of FIG. 1.

FIG. 6 is a top plan view of the door component extrusion assembly of FIG. 1; and,

FIG. 7 is a bottom plan view of the door component extrusion assembly of FIG. 1.

In FIGS. 1-5, the door component extrusion assembly is shown with a symbolic break in its length. The broken lines at the symbolic break form no part of the claimed design. The appearance of any portion of the door component extrusion assembly between the break lines shown forms no part of the claimed design.
